CHARLES T. McCUE, OF DETROIT, MICHIGAN, ASSIGNOR TO UNIVERSAL BUTTON FASTENING & BUTTON COMPANY, OF DETROIT, MICHIGAN, A CORPORATION OF MICHIGAN

ATTACHING MACHINE

Application filed March 19, 1928. Serial No. 262,691.

This invention relates to machines for attaching snap fasteners and the like and aims to provide a reliable, high capacity machine which will firmly attach snap fastener parts without distorting them and impairing their efficiency.

The nature of the invention may be readily understood by reference to one illustrative machine embodying the invention and shown 10 in the accompanying drawings.

In said drawings:

Fig. 1 is a side elevation of the machine (the front of the machine being at the right hand of the figure).

Fig. 2 is a side elevation (partly in section) of the opposite side of the machine (the front of the machine in this figure being at the left).

Fig. 3 is a front elevation (partly in section) of the machine.

Fig. 4 is a longitudinal section of the upper die member.

Fig. 5 is a section of the lower end of the upper die member showing the placing device in the act of positioning one of the fastener elements in the die.

Fig. 6 is a view similar to Fig. 5 showing the placing device withdrawn from the die.

Fig. 7 is a sectional elevation of the upper and lower dies in the act of uniting the two fastener elements to an interposed piece of fabric or the like.

Fig. 8 is a transverse section adjacent the lower end of a fastener raceway, taken approximately on line 8-8 of Fig. 3.

Fig. 9 is an enlarged perspective of the lower end of the upper die (inverted to simplify illustration) and the spring holder which in assembled position (see Figs. 5 and 6) lies in the recess at the end of the die.

Fig. 10 is a vertical central section taken on the line 10-10 of Fig. 3 showing the lower die, the placer slide associated therewith and the mechanism for releasing single elements from one of the raceways. The upper die mechanism has been omitted in this section to simplify illustration.

Fig. 11 is a perspective view of the guide-way through which the elements are fed to the lower die.

Fig. 12 is a perspective view of a sleeve which surrounds the lower die.

Figs. 13 and 14 show respectively the elements of the illustrative fastener part.

Fig. 15 is a perspective view of the stud placing mechanism.

Fig. 16 is a perspective view partly in section of a supply hopper and its operating mechanism which supplies studs to the stud receiver.

The illustrative mechanism has been designed in this instance to attach the stud or ball part 10 (Fig. 13) of a snap fastener. The attaching means is here shown as a rivet 11 (Fig. 14).

The stud part comprises a base having a projecting stud, in this case in the form of a hollow ball integral with the base. The stud is usually made from sheet metal according to well known practices; and it is of well known construction. Further description thereof is unnecessary in this connection.

The attaching rivet 11, in this instance, has a hollow stem 12 (whose height sufficiently exceeds that necessary to pass through the fabric to allow a margin for upsetting within the hollow stud of the fastener) designed to pass through the fabric to which the fastener is attached and to enter the interior of the stud and to be upset therein.

Since the opening into the interior of the ball is somewhat restricted as compared with the internal diameter thereof, the enlarged head formed inside the ball by upsetting the rivet securely holds the elements of the fastener clamped to the interposed fabric.

The elements of the fastener part above referred to are attached to an interposed web of fabric or the like by cooperating dies 13 and 14 which as they are brought together

on opposite sides of the web of fabric cause the rivet to penetrate the fabric, enter the fastener member, and to be upset therein (Fig. 7). The top of the rivet is indented (and in this case also perforated) as indicated at 15 (Fig. 14), thereby leaving a relatively square or sharp edge to the rivet so that it serves in cooperation with the stud member to punch or pierce the fabric.

The upper die mechanism comprises in ad-

dition to the dies 13 and 14, a base 16, a

slide 17, a lever 18, a spring 19, a lever 20, a

slide 21, a lever 22, a lever 23, a lever 24, a

dition to the elongated plunger 16 of the die 13, a surrounding reciprocable sleeve 17 which is slidably mounted in the stationary housing 18 of the machine. While the die 5 plunger 16 is constructed and arranged to slide within the sleeve 17, it is momentarily held immovable therein by compression spring 19, of sufficient stiffness to permit the die to yield relative to the sleeve 17 only when 10 the elements of the fastener have been sufficiently tightly compressed together on opposite sides of the fabric or when some unusual obstruction is encountered. An enlargement 15 at the upper end of the plunger 16 engages a shoulder 21 within the sleeve 17 to limit the outward position of the die relative to the sleeve. The upper end of the spring 19 bears against removable plug 22 held within the sleeve by a screw plug 23. By varying 20 the length of the plug 22 the initial compression of the spring 19 may be varied so as to supply the proper compressive force to the 25 fabric and the fastener elements.

The end of the snap fastener engaging die 25 is shaped to conform to that portion of the surface of the fastener part (in this case the ball or stud portion) which operatively engages the mating part of the snap fastener (in this case the socket part). For this purpose the lower end of die 13 is provided with 30 a recess 24 which conforms to and surrounds the projecting stud sufficiently snugly to prevent any distortion thereof during the assembly operation and the upsetting of the rivet 35 inside the stud. In this way the fastener stud suffers no change in size in the attaching operation such as would destroy its proper co-operating fit with the socket part of the fastener. When fastener studs of different sizes 40 or contours are attached a correspondingly different die 13 may be employed. Adjacent the end of the die 13 is a stud holder in the form of a loop spring 25 which holds the stud in place at the end of the die (by engagement 45 with the neck or base of the stud) prior to the assembly operation. In the present case the spring is seated in a recess 26 at the end of the die in which recess it is held by a retaining sleeve 27 having a flange 28 at the 50 lower end which extends at least partly over the recess 26 to hold the spring in place. The sleeve may be secured to the die in any appropriate manner as by a screw 29.

Individual fastener studs are placed in operative relation to the die by placing mechanism in the form of an oscillating and reciprocating arm 30 which oscillates to carry a stud into alignment with the die and reciprocates to move the stud vertically into engagement with the spring holder 25. The arm 30 is provided with a head 31 which enters the interior of the stud to locate it properly on the arm for placing purposes. The stud parts are supplied in this instance to 60 the placing mechanism by a stud raceway 32

whose cross section is such as to maintain the studs in a single column of uniformly arranged studs. The lower end of the raceway is controlled in the present case by a spring device 33 having a pair of spaced 70 spring legs 34 separated a distance slightly less than the diameter of the base of the stud, thus preventing the escape of studs from the raceway. The spring legs 34 are designed so as to separate to permit the passage of a 75 fastener when the latter is positively moved by a force somewhat greater than the pressure of the column of studs against the spring device. In this instance, the release of a single fastener in the manner above described is effected by the placer arm whose head 31 enters the lower stud and in moving forward causes the stud to spread the spring legs 34.

The studs are supplied properly arranged 85 to the raceway 32 by a hopper 35 within which rotates a disc 36 having passages 37 adjacent its periphery which permit the escape of studs from the hopper into the raceway 32 when they are located in proper position, i. e., 90 with the stud portions facing one way. The disc 36 is rotated by a sprocket 38 driven by a sprocket 39 on the shaft which drives pulley 40.

The placer operating mechanism comprises 95 in this instance an oscillating bell crank 41 mounted on a vertically reciprocating pivot rod 42. The placer 30 is adjustably mounted at one end of the bell crank arm (Fig. 15) by means of a clamp screw 43 and an adjusting screw 44. This construction permits the placer to be adjusted relative to the end of the die so that it will accurately align a fastener stud therewith. The other end of the bell crank arm is connected with a link 45 100 by means of which it is oscillated about the axis of shaft 42, thereby giving the placer device an oscillating movement between a point in alignment with the die 13 and a point 105 in alignment with the lowest fastener element 110 in the raceway 32. The link 45 is connected with a reciprocating slide 46 slidably mounted on the machine by screws 47 which pass through slots 48 therein. The slide is provided with a cam roll 49 which is actuated 115 by the main cam 50 mounted on main cam shaft 51. A spring 52 connected with the slide by means of a pin 53 serves to hold the cam roll 49 in operative engagement with the cam 50.

Pivot shaft 48 is reciprocated vertically to give the placer mechanism the necessary vertical travel, by a lever 54 pivoted at 55 to the machine and engaging the rod with its outer end 56. The inner end 57 of the lever is provided with a cam roll which engages a cam surface 58 provided by the peripheral contour of main cam 50. The cam roll is held in engagement with the cam by means of a spring 59 axially aligned with the rod 42 130

and connected at its upper end at 60 so as to exert a lifting force on the rod. The cam surface 58 is so designed as to give the head 31 on the placer 30 an upward movement when it is in alignment with die 13 to place a fastener part within the grasp of the holder 25, and then a downward movement until the head 31 clears the positioned fastener part. Thereupon the placer is moved laterally into alignment with the leading fastener part at the end of the raceway 32. At the proper time the head 31 is raised to enter the fastener part preparatory to forcing the latter between the spring legs 34. The operation of main cam 50 on cam roll 49 is, of course, coordinated with the vertical movements of the placer mechanism.

Rivets 11 are in this instance placed in operative relation to the die 14 by means of a reciprocating slide 61 (Fig. 10) which moves a single rivet forward and places it upon die 14. The die is advantageously provided with a central projection 62 which enters the hollow rivet stem so as to center and hold it on the die. A guard sleeve 63 is advantageously provided to surround the rivet to prevent its displacement by the fabric which is positioned to receive the fastener. The sleeve 63 is slidable relative to die 14 and is pressed upwardly by a spring 64 located between the lower end of the sleeve and the die housing 65. A transverse pin 66 whose ends operate within slots 67 in the sleeve serves to limit the reciprocative movement. The portion of the sleeve facing the rivet slide 61 is provided with a sort of T shaped slot to permit the entry of the rivet and its slide within the sleeve.

Slide 61 is connected with a cross-head 6 operated by the lever 70 pivoted at its upper end 71 to the machine and provided at 72 with a projection or cam roll which is operated by a cam groove on the cam 50 by means of which the lever is oscillated. A link 73 connects the lower end of the lever with the cross-head 69.

The rivet guideway 74 is covered adjacent its outer end by a shield 75 pivoted at 76 to prevent the catching of the fabric between the rivet and the lower die structure (Fig. 10) which would not only interfere with operation but would injure the fabric. The shield may raise slightly as the rivet is advanced to attaching position and may be fully raised to permit the removal of a jammed rivet.

The rivets are supplied to the guideway 74 by a raceway 77 whose cross-section is such as to hold a column of uniformly arranged rivets. The lower end of the raceway is inclined to cause a rivet to slide into the guideway 74 with its stem up. The rivets are released one by one from the raceway by a control device in the form of an oscillating disc 78 having a notch 79 therein which passes

over the stem of the lowest rivet and separates it from the column of rivets and releases it. The control device is provided with an arm 80 (Figs. 3 and 10) which is oscillated by a slide 81 having an inclined cam face 82 engaging the lower side of the arm 80, the latter being held in engagement therewith by a loop spring 83. The cam slide 81 is reciprocated from slide 61 by a projecting finger 84 (connected with slide 61) which engages 75 a pin 85 on slide 81. A spring 86 holds the pin 85 in engagement with the finger 84.

Rivets are supplied to raceway 77 from a hopper 87 of known construction placed opposite hopper 35 and operated by sprocket 38. 80

After a fastener part and its rivet have been located in operative position relative to the dies, the latter are brought together, in this instance by lowering the upper die. The upper die is in this instance operated by lever 88 pivoted to the machine at 89 and actuated by the cam groove 90 in main cam 50 into which projects a cam roll 91 at the end of lever 88. The opposite end 92 of lever 88 is rounded and enters recess 93 in the upper die sleeve 17 by means of which the die is connected with its reciprocating mechanism.

The operation of the dies and accessory mechanism is controlled in the present instance by foot lever 94 connected with a bell crank arm 95, the end 96 of which engages a clutch 97 operatively connected with the main shaft 51. A depression of foot pedal 94 withdraws the arm 96 from engagement with the clutch 97 and permits the machine to operate 100 until the pedal is released. As will appear from the foregoing description, a single rotation of main cam 50 effects a complete cycle of operations of the machine. The clutch is designed to engage the arm 96 at a point when the dies are separated so as to permit removal or shifting of the fabric. 105

When it is desired to attach a fastener part to fabric, the latter is properly located between the dies and the pedal 94 is momentarily depressed. The lower die structure is provided with guard plates 98 on opposite sides of the guard sleeve and terminating approximately level with the upper edge of the sleeve. This provides a relatively flat area 110 for support of the cloth and prevents the cloth from catching against or interfering with the operation of the guard sleeve. 115

The upper die is advantageously provided with a stripper in the form of a sleeve 99 surrounding the lower end of the die and slidable thereon. The sleeve is pressed downward to project beyond the lower end of the die by a spring 100. The pin 101 whose ends project into slots 102 in the stripper sleeve limits the downward movement of the sleeve. The slots 102 are long enough to permit the sleeve to be moved up so that its lower end is at least flush with the lower end of the die structure. Upon separation of the dies 13 120 125 130

and 14, the downward pressure of the stripper sleeve 99 strips the fastener part from its holder 25 and from the die, thereby completely releasing the fastener part and the cloth to which it has been attached from the die. By means of this arrangement the cloth is automatically released as soon as there is any opportunity to move it upon separation of the dies.

10 Obviously the invention is not limited to details of the machine herein disclosed since these may be variously modified. Moreover, it is not indispensable that all features of the invention be used conjointly since various 15 features may be advantageously employed in different combinations and sub-combinations.

Having described one embodiment of my invention, I claim:

1. A machine for attaching snap fasteners comprising in combination a die for engaging a fastener part, means for placing a fastener part in operative relation to said die, and means associated with said die for holding a fastener part in position against said die, 25 said means including a member cooperating with one end of said die to form a recess and a spring mounted in said recess.

2. A machine for attaching snap fasteners comprising in combination attaching mechanism including a die having a recess to receive a fastener part, an oscillating placing device for carrying a fastener part into alignment with said die, and means for moving said placing device into alignment with said die to place the fastener part in the recess in the die, said means including a bell crank lever and means for moving said bell crank lever in two directions.

3. A machine for attaching snap fasteners comprising in combination attaching mechanism including a die having a recess to receive a fastener part, a placing device having a lateral oscillation for carrying a fastener part into alignment with said die, and means for reciprocating said placing device to carry the aligned fastener part into the recess of the die and thereafter to withdraw the placing device.

4. A snap fastener attaching machine comprising in combination attaching mechanism including a die having a recess for receiving a fastener part, supply mechanism for supplying individual fastener parts, a placing device having a head constructed and arranged to enter the interior of a fastener part, mechanism for oscillating said placing device from a position in alignment with said supply mechanism to a position in alignment with said die and vice versa, and means for reciprocating said placing device to raise said head into a fastener part and to raise the fastener part thereon into the recess in said die.

5. A machine for attaching stud parts of snap fasteners comprising in combination a die having a recess therein conforming to the

shape of the stud portion of the fastener part, and a spring member carried by the die and having a portion substantially conforming in shape to and adapted to grip a portion of the fastener part to hold the latter in said recess. 70

6. A fastener attaching machine of the character described comprising in combination a pair of cooperating attaching dies constructed and arranged to attach a fastener to an interposed web of material, a guideway associated with one of said dies, means for passing an attaching rivet through said guideway to said die, and a pivoted shield covering said guideway to prevent contact between the web of material and the rivet 80 as the latter is being passed through said guideway.

7. A machine for attaching snap fasteners comprising in combination attaching mechanism, means for supplying fastener parts including a raceway terminating adjacent said attaching mechanism, a member carried by the raceway and having spaced spring legs positioned to prevent the escape of fastener parts from the raceway, and a positioning device including an arm mounted for auxiliary and reciprocatory movements and having a portion adapted to engage a fastener part and force the same between the legs aforesaid of said spring member and to carry 90 the released fastener part into operative relation to said attaching mechanism. 95

8. In a machine of the character described, the combination with a die, of a raceway adapted to receive a plurality of fastener parts, a flexible member normally closing said raceway, said member including a finger adapted to engage one of the fastener parts, and means for moving said finger to carry said fastener part from the raceway to a point in alignment with said die and for moving said fastener part toward said die into engagement therewith. 100

9. A device of the class described including in combination, a pair of cooperating die members, a fastener placing device for positioning a fastener adjacent one of said die members, a slide for positioning a rivet adjacent the other of said die members, and a rotatable member having a plurality of cammed portions operable to oscillate and reciprocate said fastener placing device, to actuate said slide and to reciprocate one of said die members. 110

10. In a machine of the class described, a die mechanism including a stationary housing, a reciprocable sleeve slidably mounted in the housing and having a shoulder intermediate its ends, a screw plug carried by the sleeve, a removable plug between the screw plug and shoulder, a coil spring between the removable plug and shoulder, a plunger slidable relative to the sleeve and having a portion at one end constituting a die, said plunger having another portion momentarily held by the 120

spring against said shoulder, a sleeve secured to the plunger and having a marginal flange extending over and constituting a framing for the die, a stud holder between the marginal flange and die, and means mounted for limited sliding movement on the last mentioned sleeve for stripping the stud from the holder.

11. In a machine of the class described, a die mechanism including a stationary housing, a reciprocable sleeve slidably mounted in the housing and having a shoulder intermediate its ends, a screw plug carried by the sleeve, a removable plug between the screw plug and shoulder, a coil spring between the removable plug and shoulder, a plunger slidably relative to the sleeve and having a portion at one end constituting a die, said plunger having another portion momentarily held by the spring against said shoulder, a sleeve secured to the plunger and having a marginal flange extending over and constituting a framing for the die, a stud holder between the marginal flange and die, and means for stripping the stud from said holder including a sleeve mounted for limited sliding movement on the last mentioned sleeve, the connection between said sleeves being such that the stripper sleeve is adapted to be moved up on the other sleeve so that the lower end of said stripper sleeve is substantially flush with the lower end of the plunger, and yieldable means associated with said other sleeve for moving the stripper sleeve downwardly beyond the marginal flange of the other sleeve to remove a stud from the holder.

12. In a machine of the class described, a stationary housing, a reciprocable sleeve slidably mounted in the housing, a plunger slidably mounted in the sleeve and provided at one end with a portion constituting a die, means carried by said plunger and overlapping a portion of the die for holding a stud in juxtaposition to the die, and means for placing a stud in operative relation to the die, including an arm capable of oscillatory movement to carry a stud into alignment with the die and capable of reciprocatory movement to move the stud vertically into engagement with the stud holding means aforesaid.

13. In a machine of the class described, a reciprocating plunger having a portion at one end constituting a die, means carried by said plunger at said end for holding a stud in juxtaposition to the die, a stud raceway, and means for transferring studs one at a time from the raceway to the die including an arm capable of oscillatory movement to carry a stud into alignment with the die and capable of reciprocatory movement to move the stud vertically into engagement with the stud holding means aforesaid.

14. In a machine of the class described, a stationary frame, and stud placer operating

mechanism carried by said frame and including a plate mounted for sliding movement on the frame, a cam roll carried by the plate, a cam engageable with said roll, a spring for holding the cam roll in operative engagement with the cam, a vertically reciprocating pivot rod, a bell crank lever carried by said rod, a link terminally connected to said lever and plate and adapted upon reciprocation of said plate to oscillate the lever about the axis of said rod, and a stud placer arm adjustably mounted on the bell crank lever.

15. In a machine of the class described, a main cam, a reciprocatory plate, means for reciprocating the plate including a cam roll carried by said plate and engageable with said cam, a reciprocatory pivot rod, means operable by the cam aforesaid for reciprocating said rod, a bell crank lever carried by said rod, a connection between said lever and plate causing the lever to oscillate when said plate reciprocates, and a stud placer element carried by said bell crank lever.

16. In a machine of the class described, a reciprocating pivot rod, a bell crank lever carried thereby, a stud placer element carried by said lever, a reciprocatory plate, a driving connection between said plate and lever, a cam, a driving connection between said cam and reciprocating rod, and a driving connection between said cam and plate.

17. In a machine of the class described, a cam, stud placer mechanism including a reciprocating plate and a reciprocating pivot rod, a driving connection between said cam and rod, a die, a reciprocating slide for moving rivet elements upon said die, and a driving connection between said cam and slide.

18. In a machine of the class described, a die, a fastener element guideway leading to the die, a slide for moving fastener elements longitudinally of the guideway to said die, a cam, a driving connection between said cam and slide, a fastener element raceway for supplying fastener elements to the guideway, and means for controlling the transfer of fastener elements from the raceway to the guideway, including an oscillating disk having a notch therein adapted to receive a portion of a fastener element so as to separate it from the other fastener elements in the raceway, an arm projecting from the disk, a slide having an inclined cam face engaging one side of the arm, and a driving connection from said face to said last mentioned slide, whereby said disk is also operated by the cam aforesaid.

19. In a machine of the class described, a die, a fastener element guideway leading to the die, a slide for moving fastener elements longitudinally of the guideway to said die, a cam, a driving connection between said cam and slide, a fastener element raceway for supplying fastener elements to the guideway, and means for controlling the transfer of

fastener elements from the raceway to the guideway, including an oscillating disk having means adapted to separate a fastener element from the other fastener elements in the raceway, an arm projecting from the disk, a slide for actuating the arm, and a driving connection between the first and last mentioned slides aforesaid whereby said disk is also operated by the cam.

- 5 20. In a machine of the class described, a die, a fastener element guideway leading to the die, a slide for moving fastener elements longitudinally of the guideway to said die, a cam, a driving connection between said cam
10 and slide, a fastener element raceway for supplying fastener elements to the guideway, and means for controlling the transfer of fastener elements from the raceway to the guideway, including an oscillating disk having a notch therein adapted to receive a portion of a fastener element so as to separate it from the other fastener elements in the raceway, an arm projecting from the disk, and a slide actuatable by the slide aforesaid for
15 actuating said arm.
